UNITED STATES PATENT OFFICE.

AXEL R. GUSTAFSON, OF CHICAGO, ILLINOIS.

IRONING-MACHINE.

1,170,532.

Specification of Letters Patent.

Patented Feb. 8, 1916.

Application filed July 3, 1915. Serial No. 37,925.

To all whom it may concern:

Be it known that I, AXEL R. GUSTAFSON, a citizen of the United States, residing at Chicago, in the county of Cook and State 5 of Illinois, have invented certain new and useful Improvements in Ironing-Machines, of which the following is a specification.

This invention relates to improvements in ironing machines and it is designed to provide a machine which is simple in construction and efficient in operation and which is very easily manipulated during the ironing operation.

A further object is to provide a shoe or 15 concave iron which moves in a strictly horizontal plane, thereby insuring a close and uniform engagement of its concave periphery with the padded roll.

I have devised and constructed improved 20 mechanism whereby the shoe or concave iron may be retained in engagement with the roller during the ironing operation and automatically retained in normal or inoperative relation with said roller at other 25 times, nevertheless, manually operable means are provided whereby the shoe and roller may be retained in operative relation continuously when desired, as when a number 30 of small pieces of work are being passed through the machine.

With the foregoing and other objects in view the invention consists in the combination and arrangement of parts to be hereinafter fully described in the following specification, pointed out in the appended claims and illustrated in the accompanying drawings which form a part of said specification and in which—

Figure 1 is a front elevation of my improved ironing machine. Fig. 2 is an end elevation of the same. Fig. 3 is a reverse end elevation with some of the parts of the machine shown in altered position. Fig. 4 is a top plan view with a portion of the 40 table broken away to afford a better illustration of the machine. Fig. 5 is a detail plan partly in section and is taken on line 5—5 of Fig. 1. Fig. 6 is a detail bottom plan view partly in section and is taken on line 6—6 of Fig. 1. Fig. 7 is a fragmentary rear elevation. Fig. 8 is a cross section taken on line 8—8 of Fig. 7. Fig. 9 is a section taken on line 9—9 of Fig. 4. Fig. 10 is a section taken on line 10—10 of Fig. 4. Fig. 11 is a section taken on line 11—11 of Fig. 1. Fig. 12 is a sectional

detail showing the manner of supporting the receiving board. Fig. 13 is a side view, partly in section, of Fig. 12 and is taken on line 13—13 of Fig. 12. Fig. 14 is a view 60 of the shoe or concave iron employed.

Like reference characters indicate corresponding parts throughout the several views.

In the preferred embodiment of my machine as illustrated in the accompanying drawings I provide a frame formed of parallel sides 1, 1, carrying a feed table 1^a, connected by bolts 2 to the standards 3 which are connected by the lower transverse rods 4, 5 incased in sleeves 6, 7; and by upper transverse rods 8 incased in sleeves 9 and upon the last named sleeves a receiving table 10 is supported and retained in operative relation through the 75 medium of connecting brackets 11 provided with thumb screws 12 which engage said sleeves 9. Upon the sleeve 6 and between collars 13 a foot lever or treadle 14 is pivoted which is connected by pitman 15, 70 15 with angular levers 16, 17 fulcrumed on bolts 18 carried by the frame and partly supported by springs 16^a carried by lugs 16^b secured to the frame, one end of said levers being notched or toothed as at 19 and the 80 opposite or upper end being apertured longitudinally as at 20 to receive pintles 21, 21 and 22, 22 of arms 23, 24 respectively whereby the shoe or concave iron 25 is supported.

The customary gas heater 26 is located in 90 the lower portion of the hollow concave iron 25 and the heater or burner is controlled by the valve 27 as usual which regulates the passage of gas through the pipe 28. One end of the arm 24 is projected outwardly and downwardly and its free termination is beveled inwardly as at 29 and bifurcated as at 30 to compass the shaft 31 of the padded roll 32, said shaft being journaled in bearings 33 secured to the top of 100 the frame 1 and one end of said shaft being projected beyond said frame and having a spring pressed clutch 34 slidably keyed thereon which clutch is capable of engagement with the gear 35 that runs loose on 105 said shaft and that is in mesh with a worm 36 fast on a shaft 37-journaled in bearings 38, secured to the gear casing 38^a and said shaft 37 is bevel-gear-connected as at 39 to a grooved wheel 42 of a stub transmission shaft 40 fast to a lug 41 carried by the frame, said wheel 42 is connected by a belt 110

23 with the pulley 44 driven directly by the motor 45 which is arranged upon a base plate 46 yieldingly supported upon the bolts 47 provided with springs 48 which abut 5 said base plate and a supporting bracket 49 carried by the standards 3; the bolts below the bracket 49 being provided with the adjusting nuts 50 whereby the base plate 46 may be adjusted with relation to the bracket 10 48 to take up the slack in the belt 43. Referring again to the shaft 31 the same is provided on each side of the padded roll 32 with the bearings 51 each of which is provided with a centrally formed terminal 15 socket 52 into which one end of a rod 53 extends, said rod being provided with a spring 53^a which abuts the arms 23 or 24 and the bearings 51 and projected through the arms 23, 24 and into frame extensions 20 54, 54 and there retained in position by means of set screws 55, said frame extensions above the rods 53 being connected by a rod 56 and sleeves 57.

To the relatively inner sides of the frame 25 curved arms 58 are secured by pivots 59, the free ends of said arms being capable of engagement with the notched or toothed portions of the levers, 16, 17 to releasably retain the same in adjusted position; said 30 arms, further, being provided with lugs 59^b, which are engaged by return springs 60 carried by lugs 61 projecting from the frame 1 whereby said arms are normally retained in inoperative relation.

35 Referring again to the shoe or concave iron 25, the same is of two-piece hollow formation. The face 25^a is separated from the back by the ventilating slots 25^b and is formed with an inwardly projecting stem 40 25^c which is threaded interiorly for engagement with a screw 25^d which extends through an aperture in the back of the shoe and is provided with an adjusting nut 25^e whereby the face and back may 45 be adjusted to take up shrinkage, allow for warping or expansion or the like. The face at each end is provided with end walls 25^f which are notched to receive lugs 25^g of the back whereby independent longitudinal and 50 transverse movement is obviated.

The operation of this machine is as follows: The operator stands in front of the machine or in such position as to be able to depress the treadle 14 with one foot, thereby 55 depressing the pitman 15, 15 and the notched or toothed ends of the levers, 16, 17 and bring the U-shaped ends of said levers forward thus moving the pintles 21, 21 and 22, 22 and the arms 23, 24 in a horizontal plane 60 longitudinally of the rods 53 against the tension of the springs 53^a, thus moving the shoe or concave iron 25 in a horizontal plane toward and against the padded roll 32 or against the work which is placed upon that 65 roll immediately previous to contact there-

with by said shoe. As the arm 24 moves forward the beveled and bifurcated end thereof engages with the clutch 34 and rides the same into engagement with the gear 35 which is running continuously and causes 70 the same to drive the roll shaft 31 and the roll 32. The instant pressure is removed from the treadle 14 the springs 53^a will return the arms, 23, 24 and shoe 25 to normal or inoperative position and the spring of 75 clutch 34 will disengage the same from the gear 35 thus stopping rotation of the shaft 31.

While ironing a number of small pieces as napkins, handkerchiefs and the like it may 80 be desired to retain the shoe in continuous engagement with the padded roll and to keep that roll in motion. This is accomplished by depressing the treadle in the manner previously described and then manually 85 depressing the arms 58 into engagement with the notched or toothed portions of the levers 16, 17. The mechanism is stopped of course, by manually disengaging the arms 58 and levers 16, 17. 90

Having thus described my invention, it will be obvious to others skilled in the art to which it appertains, that numerous modifications and refinements thereof are possible and the same I endeavor to embody in the 95 appended claims.

What is claimed is:—

1. In a motor driven ironing machine comprising a frame and a shafted padded roll and a clutch on the shaft of said roll whereby the same may be operatively connected to said motor, horizontally disposed bearings arranged upon the roll shaft at each end of said roll, rods connecting said bearings and the said frame, angular arms 100 slidable over said rods, one of the said arms being extended for operative engagement with said clutch; springs interposed between said arms and bearings upon said rods, a shoe carried by said angular arms, pivotally supported levers operatively engaging said angular arms and a foot lever connected to said levers whereby the same may be actuated to move said shoe into engagement with said padded roll. 110

2. In a motor driven ironing machine comprising a frame and a shafted padded roll and a clutch on the shaft of said roll whereby the same may be operatively connected to said motor, horizontally disposed bearings arranged upon the roll shaft at each end of said roll, rods connecting said bearings and the said frame, angular arms slidable over said rods, one of said arms being extended and terminally beveled and bifurcated for operative engagement with said clutch; springs interposed between said arms and bearings upon said rods, a shoe carried by said angular arms, toothed levers operatively 120 engaging said angular arms, a foot lever 125

115

120

125

130

connected to said levers whereby the same may be depressed to move said shoe into engagement with said padded roll, pivotally supported arms carried by said frame for engagement with the toothed portions of said levers whereby they may be releasably retained in depressed relation and return springs for said last named arms.

3. In an ironing machine, a normally stationary power driven padded roll, a horizontally movable shoe capable of engagement with said padded roll, means yieldingly connecting said members whereby they are spaced away from each other, angular 15 arms supporting said shoe, one of said arms

being extended to coöperate with the shaft of said padded roll and foot-controlled means operatively connected to said angular arms whereby they may be actuated and caused to actuate said shoe and to coöperate with said roll shaft to connect the same with the source of power.

In testimony that I claim the foregoing as my own I have hereto affixed my signature in the presence of two subscribing witnesses.

AXEL R. GUSTAFSON.
